AIRCRAFT PROPULSION MECHANISM

Ralph B. Davis, Prestonsburg, Ky.

Application November 2, 1944, Serial No. 561,590

2 Claims. (Cl. 170—135.6)

1

This invention relates to improvements in propeller mechanisms.

The primary object of the present invention is to render the use of so-called jet propulsion devices feasible and practical as a propellant for airplanes.

Another object is to provide a propeller mechanism for airplanes wherein propeller blades carried on a rotatable hub serve to propel the planes at the comparatively low speeds involved in the initial stages or "take-off" of a flight and jet reaction motive force units are used for propelling the plane after the latter has attained a suitable speed following the take-off.

A still further object is to utilize the jet reaction motive force unit for revolving the propeller blades during the "take-off," after which the propeller blades are rendered inactive and the jet units are relied upon for propelling the plane.

With these and other objects in view, the invention consists in certain details of construction and combinations and arrangements of parts, all as will hereinafter be more fully described and the novel features thereof particularly pointed out in the appended claims.

In the accompanying drawing—

Figure 1 is a sectional view through the blades and hub of the propeller proper, the jet reaction motive force units and portions of the actuating mechanisms for certain structural parts being shown more or less schematically;

Fig. 2 is a diagrammatical view, in side elevation, illustrating the adjustment of the jet units for revolving the propeller; and

Fig. 3 is a top plan view illustrating diagrammatically the adjustment of the jet units when they serve for propelling the plane.

As illustrated, the propeller mechanism comprises jet reaction motive force units 10 carried at the outer or distal ends of propeller blades 11 which, in turn, are secured in what may be termed the propeller hub 12. This hub portion 12 is rotatably supported in bearings 13, 14 in a bearing housing 15 which may serve for mounting the propelling mechanism on the fuselage 16 of the plane. A thrust bearing 17 for the propeller hub may also be provided in said bearing housing.

The hub 12 is formed with radial sockets or bearing sleeves 18 in which the hub ends 11a of blades 11 are rotatably supported between suitable means such as abutments 20 for limiting movement of the blades in their sockets radially of the hub. The distal ends of blades 11 are

2

formed with cylindrical bearing surfaces 21 on which the jet units 10 are rotatably supported. For instance, each unit 10 may have a laterally extending sleeve 22 formed with an interior bearing surface conforming to the bearing surfaces 21 of the blades. Fuel is supplied to the jet units through radial branches 23 of a rotatable fuel line 24 connected to the main fuel line 25. The latter is, of course, fixed or stationary and a suitable stuffing box is provided at the junction between this fixed section of the line and the rotatable section 24.

The propeller blades are adapted to be rotated or adjusted in their respective sockets so that when the jet units are the sole means of propelling the plane, the blades can be turned edge-wise or to a position in which they will offer the slightest resistance to the flight of the plane. For this purpose, the inner ends of each pair of 15 opposed blades may be formed with ring gears 26 which are connected to a worm gear 27 mounted on shaft 28 driven by an electric motor 29. As the two opposed blades must be turned in opposite directions when moving to and from 20 their feathered or edge-wise positions, one ring gear 26 is connected directly to gear 27 by a gear 30 on shaft 28 and the other ring gear 26 is engaged by a gear 31 on shaft 32 which also carries a gear 33 in mesh with a gear 34 on a shaft 25 30 28.

For rotating the jet units 10 on their respective blades 11, sleeves 22 of the jets may be formed with ring gears 35 with which gears 36 mesh, said gears 36 being mounted on shafts 37 35 provided with worm gears 38 driven by electric motors 39. Current for motor 29 and motors 39 is supplied from lines 40, 41, respectively, which may be connected by brushes to copper rings 42 mounted on but suitably insulated from the supply line section 24. Each motor is connected to these rings by suitable wiring which has been omitted from the drawing to avoid confusion.

Referring to Fig. 2, the jets are shown positioned so that the force generated thereby will 45 be exerted, as indicated by arrow A, in a plane at right angles to the propeller hub and in which the propeller blades 11 are normally revolved in the take-off of the plane. It will also be observed that the blades themselves, shown in dotted lines 50 in Fig. 2, are positioned to offer maximum resistance to the air or to generate their maximum propelling force. After the plane has attained a suitable high rate of speed, the circuit through wires 41 is closed and motors 39 energized to 55 turn the jet units to the positions shown in Fig.

3 or parallel to the propeller hub 12 in line with the direction of flight of the plane and the circuit through lines 40 is closed to energize motor 29 to revolve the blades in their sockets and feather them, as shown in Fig. 3. Under these latter circumstances the jet reaction motive force units 10 serve to propel the plane, as indicated by arrows B, and the propeller blades 11 are temporarily functionless. Thus the less efficient mode of propulsion for high speeds, represented by the propeller blades, is used for propelling the plane during the "take-off" or initial portion of the flight, during which period the jet mode of propulsion would be comparatively inefficient and the more efficient form of propulsion for high speeds, represented by the jet units, is used as the propelling means only during that period of the flight when high speeds are possible or permissible. At the same time, the motive force of the jet units is utilized during the "take-off" to actuate the propeller blades.

As the propeller blades 11 and the entire hub structure revolve as a unit, motors 29, 39 can be mounted in the interior of the hub and bearings can be provided at suitable points for the several shafts 28, 32 and 37 but it is deemed unnecessary to illustrate these details or the switches for controlling the circuits through the electric power lines 40, 41.

What I claim is:

1. In a propeller mechanism for airplanes, a propeller shaft, a plurality of propeller blades rotatable on said shaft for propelling the plane forwardly at relatively low speeds, jet reaction motive force units at the distal ends of said blades, means for adjusting said units relatively to said blades to render said units effective either in the plane of rotation of said blades on the shaft to revolve said blades or in a plane transverse of said plane of rotation to propel the airplane for-

wardly at relatively higher speeds, and means for altering the pitch of the propeller blades to render them ineffective when the airplane is propelled by the influence of said jet reaction units.

5 2. In a propeller mechanism for airplanes, a rotatable hub having radially disposed bearing sleeves, propeller blades for propelling the airplane forwardly, said blades being journaled in said sleeves, jet reaction motive force units pivotally supported at the distal ends of said blades, said units being normally effective at right-angles to the center of rotation of the hub to rotate the blades and said hub during flight of the plane at low speeds and adjustable to a position parallel to the direction of flight of the plane to propel the plane forwardly at higher speeds, means for rotating said units to adjust them to either of said positions, and means for turning the individual blades in their respective bearing sleeves to minimize their propelling power when said units are in their plane propelling position.
